(57) **CLAIM**

The ornamental design for a TIRE FOR WHEELCHAIR as shown and described.

DESCRIPTION

FIG. 1 is a perspective view of a TIRE FOR WHEELCHAIR showing my new design;

FIG. 2 is a front view thereof;

FIG. 3 is a right side view thereof, the left side view being a mirror image thereof;

FIG. 4 is a fragmentary enlarged front view of the portion 4 framed in FIG. 2;

FIG. 5 is a fragmentary enlarged view of the portion 5 framed in FIG. 4;

FIG. 6 is an end view taken along line 6-6 in FIG. 5;

FIG. 7 is an end view taken along line 7-7 in FIG. 5; and

FIG. 8 is a fragmentary enlarged perspective view of the portion 8 framed in FIG. 1

Broken lines shown in the drawings are intended to show portions of the tire for wheelchair that are not being claimed, and thus illustrative purpose only and form no part of the claimed design.
